ELECTRICAL CONNECTION

Thomas D. Monroe, Owosso, Mich., assignor to
Redmond Company, Inc., Owosso, Mich., a corporation of Michigan

Application May 5, 1948, Serial No. 25,185

2 Claims. (Cl. 285—6.5)

1

This invention relates to connections, and particularly to the connection of a conduit to a receptacle, such as a machine housing, or a terminal current supply panel.

It is common to have machine housings, or supply panels, so constructed or disposed as to render it difficult to connect a circuit lead, or other conduit, to a terminal post or socket within such housing or panel. Frequently there is only a hole in the housing or panel through which the lead or conduit is to pass in order to complete a circuit path to a fitting on the interior, with no readily accessible approach to the inner side of the housing or panel, adjacent to such hole. In such situations it is desirable to have a method of effecting an anchorage and grounding of the lead or conduit to such housing or panel, which method will not require manipulation of any element on the inner side of the structure. An object of the present invention is to provide such a method of anchoring and grounding a lead upon such a structure.

A second object of the invention is to provide novel means for coupling an electrical conduit to a structure containing an element with which such conduit is to cooperate.

A third object is to provide a novel coupling of the character described, a feature of the coupling being its division into complementary sections, each of which sections is separately attachable to the supporting receptacle by insertion through an aperture in the wall thereof; this novel method of attachment permitting use of self-retaining rims on the complementary sections, as the rims, when subsequently turned into proper angular interrelationship, prevent withdrawal of the coupling from the receptacle.

A further object is to provide, in a coupling of the character described, novel means for securing the complementary coupling sections, one to the other, and to the electrical conduit received therein.

Other objects and features of the invention will suggest themselves as the following description is read in conjunction with the accompanying drawing wherein:

Fig. 1 is a view of a connector embodying the invention, as it appears when anchored to a wall, through an aperture therein, and with a conduit received within the connector;

Fig. 2 is an elevation view of one of the complementary sections of the connector;

Fig. 3 is a sectional view along line 3—3 of Fig. 2;

Fig. 4 is a view at a right angle to the view point of Fig. 2 and

Fig. 5 is an end view of the structure of Fig. 2.

It will be seen that each complementary section of the connector includes a semi-cylindrical central portion 11 of a certain radius, a semi-

2

cylindrical end portion 12 of the same radius, but with flat extensions or lugs 13, 14 on opposite sides thereof, a neck portion 15 of reduced radius, and an outwardly flaring portion 16 forming a rim at the end of the neck portion 15. Two fingers 17, 18 extend from one side of central portion 11, and a single finger 19 extends from the opposite side of central portion 11, in the region thereof that lies between the fingers 17, 18 of the mating half (see Fig. 1). The surface of portion 11 is pressed outwardly along the line of each tooth, so that the teeth are at slightly greater radial distances from the central axis, as compared with the radius of the main surface of portion 11.

Each extension 13, 14 is apertured to receive screws 21, 22, respectively, which screws pass through both halves of the connector and receive clamping nuts 23, 24, as indicated in Fig. 1.

20 The connector is installed in an opening in a wall, such as the wall 26 of Fig. 1, by tilting each complementary half, individually, through a sufficient angle to allow its rim 16 to enter the wall opening; it being noted that the radius of the wall opening is not much greater than the outer radius of the neck 15, and is considerably less than the radius of rim 16, although each rim in itself is fore-shortened, arcuately, so that its arcuate extent is sufficiently curtailed to permit its passage through the wall opening at any one of a wide range of tilting angles, when each connector section, in sequence, is tilted out of its normal relationship to the other.

After both halves of the connector have thus 35 been maneuvered so that their two rims 16 are within the wall opening, they are then worked around into parallelism, with their complementary edges in registry, and with tooth 19 of each half passing between teeth 17 and 18 of the opposite half.

30 Screws 21, 22, and nuts 23, 24 are then applied, so that nuts 23, 24 engage turned edges 31, 32 of the ears 13, 14 respectively, by which edges they are held against loosening movement. The conduit 34 is then inserted, until it reaches the neck portion 15, and screws 21, 22 are then given their final tightening, so that embossment 36 (Figs. 2 and 3) firmly grips the conduit.

What I claim is:

50 1. A conduit connector comprising two complementary sections, each having an end portion insertable in a wall opening, said end portions being arcuately preshortened to substantially less than 180°, to allow insertion of each of said end portions from any one of a wide range of oblique angles, said end portions also being of such extent, in a transverse direction with respect to the axis of said opening, as to prevent their withdrawal through said opening when said sections are positioned in parallelism and

including intercalated peripherally clasping fingers on said sections and constituting integral extensions thereof, said peripherally clasping fingers being formed on arcs whose radii slightly exceed that of said sections.

2. A conduit connector comprising two complementary sections, each having an end portion insertable in a wall opening, said end portions being arcuately preshortened to substantially less than 180°, to allow insertion of each 10 of said end portions from any one of a wide range of oblique angles, said end portions also being of such extent, in a transverse direction with respect to the axis of said opening, as to prevent their withdrawal through said opening when 15 said sections are positioned in parallelism and

including intercalated peripherally clasping fingers on said sections, as integral extensions thereof, to facilitate locking of one section to the other.
